(57) **CLAIM**

The ornamental design for the seat, as shown and described.

DESCRIPTION

FIG. 1 is a perspective view of a seat comprising the new design;

FIG. 2 is a top view thereof;

FIG. 3 is a front view thereof;

FIG. 4 is a right side view thereof, where the left side is a mirror image thereof;

FIG. 5 is a rear view thereof; and,

FIG. 6. is a front view of an alternative embodiment of said new design having an indeterminate width, which is the sole difference between it and FIGS. 1-5.

The broken lines in the figures are for illustrative purposes only and form no part of the claimed invention.
